[57] CLAIM

The ornamental design for a goblet or similar article, substantially as shown and described.

DESCRIPTION

FIG. 1 is a side elevational view of a goblet or similar article showing my new design in the size and proportions of a wine goblet;

FIG. 2 is a sectional view taken along line 2—2 of FIG. 1;

FIG. 3 is a bottom view thereof;

FIG. 4 is a sectional view taken along line 4—4 of FIG. 1;

FIG. 5 is a side elevational view of a goblet or similar article showing my new design in the size and proportions of a sherbet goblet; and

FIG. 6 is a side elevational view of a goblet or similar article showing my new design in the size and proportions of a water goblet.

Fig. 1.

Fig. 5.
